UNITED STATES PATENT OFFICE.

CHARLES MCKEEN, WILLIAM BAYES, AND WILLIAM HEYER, OF WINSIDE,
NEBRASKA.

BELT-GUIDE.

SPECIFICATION forming part of Letters Patent No. 697,354, dated April 8, 1902.

Application filed August 14, 1901. Serial No. 71,982. (No model.)

To all whom it may concern:

Be it known that we, CHARLES MCKEEN, WILLIAM BAYES, and WILLIAM HEYER, citizens of the United States, and residents of 5 Winside, in the county of Wayne and State of Nebraska, have invented a new and Improved Belt-Guide, of which the following is a full, clear, and exact description.

Our invention relates to belt-guides—that 10 is, to instruments used for preventing belts from being misplaced and saving them from undue wear and tear.

Our invention relates more particularly to a belt-guide made of separable members 15 hinged together for the purpose of applying the guide to a belt while in action or removing the same therefrom.

Our invention not only prevents the belts 20 from being misplaced by sudden gusts of wind either vertical or horizontal, but likewise prevents undue wear of the edges of the belt and prevents stretching and turning of the belt.

Our invention protects both of the flat sides 25 of the belt and both edges thereof and prevents abrasion of the belt in case the same may become accidentally twisted or misshapen from any cause whatever.

The invention consists of novel features and 30 parts and combinations of the same, as will be fully described hereinafter and then pointed out in the claims.

Reference is to be had to the accompanying drawings, forming a part of this specification, 35 in which similar characters of reference indicate corresponding parts in both the views.

Figure 1 is a perspective view of our device, and Fig. 2 is an elevation showing certain parts in section.

40 The frame of our device consists of a base-plate 1, which is provided with stake-holes 2, which are engaged by stakes 3. Secured upon the base-plate 1 are the braces 4, which engage flat boards 5 5 and hold the same rigidly

45 in position at all times. The flat boards 6 6 are connected rigidly together by the piece 8, so as to form a U-shaped member which fits upon the boards 5 5. It will thus be seen that as the members 5 5, mounted upon the 50 frame 1, are connected by the beam 7 they constitute one U-shaped member, while the

parts 6 6, connected by the board 8, constitute another U-shaped member. These members are connected by means of a hinge 17, (shown in Fig. 2,) so that the upper U-shaped member can be thrown over to the right. The nails or pegs 9 are for the purpose of steadyng the frame by means of guy-ropes 10, which are connected with stakes 11, driven in the ground. At 12 12 and 13 13 are shown 60 vertical idle rollers, which are mounted in the angular clips 20. The idle rollers 14 15 16 lie directly across the structure, as shown in Fig. 2, the upper and lower rollers being mounted in suitable bearings formed in plates 65 23 23. The middle roller 16 is mounted in semi-cylindrical bearings in the respective tops and bottoms of the U-shaped members and at the line of separation between the same, so that by throwing the upper U-shaped member 70 over to the right the roller 16 is disengaged and can be taken out. Upon the side of the frame opposite the hinge 17 there is a clasp 18, secured in a staple 24 in the left-hand member 5, so arranged as to engage the 75 staple 25 in the member 6. A hook 19, secured to a staple 27 in the member 6, is capable of engaging the staple 25, so as to retain the clasp 18 in position. The roller 16 is mounted upon trunnions 22, and being removable may be used or not, as desired. When this roller is in place, the rectangular space inside the several other rollers is divided into two parts which can be used independently for engaging a belt, and, if desired, 85 one belt can be run within the upper part, while another belt can be run within the lower part.

The operation of the device is as follows: 90 When it is desired to apply the belt-guide to a belt not in action, the frame is staked to the ground, as above indicated, and the belt placed in position either between the rollers 13 13 and 14 16 or between the rollers 12 12 and 15 16, or by taking out the roller 16 the 95 belt can be placed between the rollers 14 15, so as to have free vertical play between these two rollers. If, however, the belt is in action, the upper member of the frame is tilted over by means of the hinge 17, the belt is 100 carefully engaged, the roller 16 being placed in position or omitted, as desired, and the

clasp 18 being locked in position by the hook 19, and the frame is set upon the ground. The stakes 3 are now driven in position and the guy-ropes 10 are secured to the nails or pegs 9 and to the stakes 11. To remove the device from a belt in action, all that is necessary to do is to disengage the hook 19, unlock the clasp 18, tilt over the upper hinged member, and remove the structure from the belt.

Having thus fully described our invention, we claim as new and desire to secure by Letters Patent—

1. A belt-guide, comprising a frame provided with a belt-receiving aperture and separable into two members flexibly connected together, each of said members being provided with rollers disposed at different an-

gles relatively to each other, for the purpose of engaging independent surfaces of the belt. 20

2. A belt-guide, comprising a frame made of substantially U-shaped members hinged together, a clasp for rigidly securing said members in the general shape of a rectangle, and an idle roller disposed directly across 25 said rectangle so as to separate the same into compartments.

In testimony whereof we have signed our names to this specification in the presence of two subscribing witnesses.
